AUTOMATIC PHONOGRAPH

John J. Heins, Jr., Abington, Pa., assignor to
Philco Radio and Television Corporation,
Philadelphia, Pa., a corporation of Delaware

Application November 24, 1941, Serial No. 420,304

9 Claims. (Cl. 274—10)

This invention relates to automatic phonographs, and is especially concerned with machines of the drop-table type, i. e., those in which changing of the records is effected by dropping successive records onto the turntable from a record-supporting structure arranged thereabove.

More particularly, the invention has reference to machines of this general type, which utilize a central non-rotative spindle adapted to support a stack of records above the turntable, and in which suitable mechanism is provided for causing the lowermost record to slide down into playing position when the tone arm is swung off of the turntable.

It has been found that such machines are subject to certain difficulties, which arise from the fact that shocks may be transmitted from the turntable, or the cabinet structure, to the record-supporting spindle. This often causes the machine to drop two records at once during the change cycle, as the impact of the first record striking the turntable may transmit sufficient vibration to the supporting spindle to shake another record loose from the small retaining shelf formed in the upper portion of said spindle. Similarly, a shock to the cabinet during the playing of a recording, as by slamming a lid or the like, often resulted in the dropping of an additional record onto the top of the tone arm, with possible consequent damage to both the pick-up and the recordings.

With the above in mind, it is the primary object of the present invention to eliminate the aforesaid difficulties, by the provision of a record-supporting structure of such a character that shocks of the above type are prevented from interfering with the proper operation of the mechanism.

It is a more particular object of the invention to provide a non-rotative record-supporting spindle, which although positioned by the central turntable bearing structure through which it passes, is mounted with freedom to float somewhat with respect thereto.

It is also an object of the present invention to provide a structure of the above type which is of simple and compact construction, and in which the freedom for floating will be positively maintained within the desired values.

The manner in which the above objects and advantages are realized together with others incident to the invention, will be clear from a consideration of the following description, taken with the accompanying drawings, in which:

Fig. 1 is a sectional view of an automatic phonograph embodying this invention;

Fig. 2 is a sectional view on a larger scale, illustrating the record supporting spindle and the structure with which it cooperates;

Fig. 3 is a sectional view taken on the line 3—3 of Fig. 2, with the securing nut removed;

Fig. 4 is a sectional view on an enlarged scale, taken as indicated by the section line 4—4 of Fig. 2;

Fig. 5 is a view similar to Fig. 2 illustrating an alternative form of the invention; and

Fig. 6 is a sectional view on a larger scale of a portion of the mechanism shown in Fig. 5.

15 Referring more particularly to the drawings, Fig. 1 illustrates the essentials of one form of automatic phonograph embodying the invention. The baseplate, indicated at 1 carries the usual tone arm 2, by means of a compound pivot 3, accommodating both swinging and vertical movement of said tone arm. The baseplate is provided with a central recessed portion 4 in which is mounted the turntable 5. A central turntable hub 6 is provided, riveted to the turntable as at 6a, and at its lower end carries crown-gear teeth 7 (see Fig. 2) adapted to engage, but normally spaced from, similar teeth 8, formed on the upper face of a lower gear member 9.

Hub member 6 and gear 9 are both rotatably carried by a hollow post 10, which extends from the plane of the upper face of the turntable, down through an aperture formed in a depending U-shaped bracket 11. This post also cooperates with the record-supporting spindle S in a manner which will be fully described later.

A bushing 12 serves to rotatably mount the turntable on the post, the vertical thrust being taken by a circular flange 13, formed on the post 10, and cooperating with a washer 14 40 against which the hub 6 bears. To provide a power take-off for the cycling mechanism, gear member 9 is mounted with freedom for axial movement, against the pressure of a spring 15, into engagement with the teeth 7 formed on hub member 6. This vertical movement is effected by a lifting fork 16, pivoted at 17, and actuatable by means of a solenoid 18, shown in Fig. 1. As clearly appears in Fig. 4, gear member 9 is equipped with spur teeth 19 which cooperate with an idler gear 20 (see Fig. 1) which in turn meshes with teeth 21 formed on the circumference of a master cam 22.

As the particular cycling cam and gear train used form no part of the present invention, per 50 se, and are fully described and claimed in U. S.

Patent 2,339,981 granted January 25, 1944, they need not be particularly described here. However, it should be mentioned that cam 22 is provided with a number of different cam surfaces, which operate (in response to the energization of solenoid 18 and consequent engagement of gear teeth 1 and 8) to raise the tone arm and swing it off the record, and also to actuate the record support and release mechanism now to be described.

As best appears in Figs. 1 and 2, a plurality of records R are supported at their centers by the upper portion of spindle S, which has a flat shoulder 23 formed to engage the underside of the lowermost record at its center opening. The outer edge of the bottom record is supported by either one of two shelves 24 and 25, depending upon the size of the records to be played. Each shelf carries projections 26 shaped to engage the underside and the edge of the bottom record, as appears in Fig. 1; the shelves, in turn, being carried by an upstanding post 27, fixed to an actuating arm 28 which is pivoted to the frame of the machine at 29. Post 27 and arm 28 form a bellcrank which is actuated by a cam projection (not visible) formed on the lower face of master cam 22, to move the shelf structure slightly toward the spindle S. This pushes the lower record past the edge of shoulder 23, and allows it to drop onto the turntable. To aid in preventing the dropping of more than one record, spindle S is provided with a pivoted pawl 30 (see Fig. 2) which serves to urge all but the lowermost record somewhat toward the right as viewed in Fig. 1.

However, as mentioned previously, the impact of a record falling on the turntable (as well as other shocks) is often sufficient to cause such vibration of spindle S, as to shake an additional record past pawl 30 and shoulder 23, and cause it to drop upon the turntable. This difficulty is eliminated by a floating spindle mounting, one form of which is illustrated in Figs. 2 and 3.

Spindle S extends downwardly through post 10, and the cooperating surfaces of the post and spindle are carefully machined to allow movement of the spindle within the post, of about $\frac{1}{16}$ of an inch. This value may vary but must be kept small enough so that any movement of the spindle which may occur during playing of a recording, will be of so small an extent as to produce no objectionable eccentricity of the rotating record. The clearance may be clearly seen in Fig. 2. At their lower extremities both post and spindle are provided with reduced portions, and the clearance therebetween is still maintained. The reduced portion of post 10 provides an annular shoulder 31 which cooperates with washers 32-32 and securing nut 33, to fasten post 10 to U-shaped bracket 11, and thereby maintain the post in proper vertical alignment.

It will be evident that the lower end of spindle S might be fastened in a number of different ways, while still maintaining the desired clearance between said spindle and the inner wall of the hollow post.

However, for the purpose of increasing the vibrational isolation, the embodiment illustrated provides novel spindle securing structure. Spindle S is fixed against rotational and axial movements, by a transverse pin 34 extended through the spindle and post 10, and seated in a pair of oppositely facing recesses 35-35 (see Fig. 3), formed in the lower face of bracket 11. As

brought out later, this constitutes a lost motion connection.

To facilitate assembly of the mechanism, post 10 flares outwardly in its middle region to provide a diameter at least as great as that of annular shoulder 13. As the post must be inserted through the aperture in bracket 11 from above, this allows the inside diameter of the bearing surface of gear 9 to be great enough to permit passage of the gear over shoulder 13, after the post has been inserted and fastened at its lower end. The hub of the turntable is, of course, passed downwardly over the spindle S and into contact with the upper face of shoulder 13, after gear 9 is positioned.

In Figs. 5 and 6, there is illustrated an alternative form of spindle mounting, which, although permitting the same desired clearance between the post and the spindle, varies in the manner of fixing the lower end of said spindle. Referring particularly to Fig. 6, post 10 is provided with internal threads 36 at its lower end, which cooperate with a reduced threaded portion 37 of spindle S, there being considerable play between the cooperating threads. A pair of washers 32-32 and a nut 33 again serve to secure shaft 10 to bracket 11. The lowermost extremity of spindle S is of non-circular form and cooperates with a suitable complementary aperture formed in a small bracket 38, to hold the spindle against rotation.

In both of the forms illustrated, the lower spindle securing means is in the nature of the preferred lost motion connection, which although securing said spindle against rotational and axial movements, has sufficient play to insure that vibrations communicated from the turntable and cabinet structure to the bracket 11, will not substantially affect the position of the spindle. In the first form this is achieved by the relatively loose connection between pin 34, post 10 and the recesses 35; while in the second form, there is appreciable play between the threads 37 formed on spindle S and the cooperating internal threads 36 of post 10. It should be noted that this connection is effected adjacent the lower ends of the spindle and post, i. e., at a point well removed from the surface of the turntable where most of the shocks arise. Moreover, as these elements are connected to a depending bracket which is part of the main framing of the machine, any vibrations which might travel down post 10, will be substantially dissipated in the main framing, without affecting the spindle.

From the foregoing it will be evident that this invention provides an automatic record changing mechanism which employs the simple, inexpensive drop-type of change structure, but which is not subject to difficulties heretofore encountered in such devices, as the record spindle, although positioned by the turntable support structure, is vibrationally isolated therefrom.

In addition, the floating spindle-support structure of the invention not only provides an adequate solution to the problems set forth, but does so without complicating the phonograph mechanism, or adding materially to its cost.

While two preferred forms of the invention have been illustrated, it will be evident that the device might be modified in certain respects without departing from the spirit of the invention. In general, the invention contemplates such changes as may fall within the scope of the appended claims.

I claim:

1. In an automatic phonograph of the type having a rotatable hub, means for supporting a stack of records above a turntable and mechanism for successively dropping said records into playing position, a central record-supporting spindle extending upward through the hub of the turntable, and means arranged below the surface of said turntable for supporting said spindle against rotative and axial movements, and for positioning said spindle in spaced relation to said hub, thereby isolating the record-supporting means from shocks arising in the turntable and its supporting structure.

2. In an automatic phonograph of the type having means for supporting a stack of records above a turntable and mechanism for successively dropping said records into playing position, a central record-supporting spindle extending upward through a hub of the turntable, and means arranged below the surface of said turntable for supporting said spindle against rotative and axial movements, and for accurately positioning said spindle with respect to said hub, said spindle-supporting means comprising a hollow non-rotative post to which said spindle is loosely coupled.

3. An automatic phonograph comprising a turntable, central bearing means for rotatably supporting said turntable, means including a non-rotative spindle for supporting a stack of records above the turntable, and mechanism for successively dropping said records into playing position, said spindle extending down through said bearing means in spaced relation thereto and being coupled to a lower portion thereof through a lost motion connection, whereby said spindle is effectively isolated from shocks or vibrations.

4. An automatic phonograph comprising a turntable, a central hollow bearing shaft for said turntable, means including a non-rotative spindle for supporting a stack of records above the turntable, mechanism for successively dropping said records into playing position, the lower portion of said spindle being extended downwardly through said bearing shaft in spaced relation thereto, and means providing a lost motion connection between said bearing shaft and said spindle, and normally serving to maintain said spindle in spaced relation to the inside wall of said shaft.

5. A construction in accordance with claim 4, wherein both said shaft and said spindle are provided near their lower extremities with interfitting reduced portions, and wherein said lost motion connection is effected between said portions.

6. An automatic phonograph comprising a

turntable, a central hollow bearing shaft for said turntable, means including a non-rotative spindle for supporting a stack of records above the turntable, mechanism for successively dropping said records into playing position, the lower portion of said spindle being extended downwardly through said bearing shaft in spaced relation thereto, and means comprising a pin and slot connection between said shaft and said spindle for providing lost motion therebetween, whereby said spindle is effectively isolated from shocks or vibrations.

7. A construction in accordance with claim 6, in which a transverse frame member is provided below the turntable, means securing the lower portion of said shaft to said frame member, said pin extending outwardly from said shaft into engagement with said frame member, whereby said spindle is held as against rotational movement.

8. An automatic phonograph comprising a turntable, a central hollow bearing shaft for said turntable, means including a non-rotative spindle for supporting a stack of records above the turntable, mechanism for successively dropping said records into playing position, the lower portion of said spindle being extended downwardly through said bearing shaft in spaced relation thereto, means providing a lost motion connection between said bearing shaft and said spindle, and normally serving to maintain said spindle in spaced relation to the inside wall of said shaft, said last-mentioned means comprising cooperating internal and external threads formed on said shaft and said spindle respectively, and means securing said spindle against rotational movement.

9. An automatic phonograph comprising a turntable, a central hollow bearing shaft for said turntable, means including a non-rotative spindle for supporting a stack of records above the turntable, mechanism for successively dropping said records into playing position, the lower portion of said spindle being extended downwardly through said bearing shaft in spaced relation thereto, means providing a lost motion connection between said bearing shaft and said spindle, and normally serving to maintain said spindle in spaced relation to the inside wall of said shaft, said last-mentioned means comprising relatively coarse internal and external threads formed on said shaft and said spindle respectively and providing a lost motion connection therebetween, and a member engaging said spindle to restrain it against rotational movement.

JOHN J. HEINS, JR.
